2 Sheets-Sheet 2

UNITED STATES PATENT OFFICE

CHARLES EDWIN SHEPPARD, OF NEW YORK, N. Y.

BINDER

Application filed April 19, 1929. Serial No. 356,392.

This invention relates to loose leaf binders, and more particularly to a hinged binder having a new and improved catch mechanism.

5 The invention provides a simplified catch for a loose leaf binder which may be selectively locked in a plurality of positions and in which the catch may be released by the same manual operation that is required to 10 open the binder. The invention accordingly permits a single operation to be employed for releasing the catch mechanism and extending the binder to open position.

The invention further provides a simplified means for mounting arcuated leaf posts whereby they may be readily inserted in aligned position concentrically with the axis of the binder hinge. For this purpose the posts are formed with an integral shoulder 20 and plane surfaced shanks which cooperate with holes of a similar shape in the binder elements for suitably aligning the posts, the ends of the shanks being adapted to be riveted into engaging position for securing the 25 posts in the binder without the use of additional guiding elements.

In accordance with the present invention a plurality of cooperating latch members are provided at separated points along the hinged 30 elements of the binder. Each of the latch members is provided with a plurality of catches whereby the binder may be locked in closed or in partly opened positions. The latches are controlled by a thumb lever which 35 is positioned adjacent the end of the binder and is movable in a direction transverse to the axis of the binder hinge whereby a single motion of the hands may be employed for releasing the catch and for opening the 40 binder.

The invention also consists in certain new and original features of construction and combinations of parts hereinafter set forth and claimed.

45 Although the novel features which are believed to be characteristic of this invention will be particularly pointed out in the claims appended hereto, the invention itself, as to its objects and advantages, the mode of its 50 operation and the manner of its organiza-

tion may be better understood by referring to the following description taken in connection with the accompanying drawings forming a part thereof, in which

Fig. 1 is a plan view of the binder in open 55 position;

Fig. 2 is a side elevation of the binder in open position;

Fig. 3 is a plan view of the binder in partly 60 open position with fragmentary sections of the frame pieces removed to show details of the latch device;

Fig. 4 is a section taken on line 4—4 of Fig. 3;

Fig. 5 is a section taken on line 5—5 of 65 Fig. 4; and

Figs. 6, 7 and 8 are enlarged details of the improved leaf post.

Like reference characters denote like parts 70 in the several figures of the drawings.

In the following description and in the claims parts will be identified by specific names for convenience, but they are intended to be as generic in their application to similar parts as the art will permit.

Referring to the drawings more in detail the invention is shown as applied to a binder comprising a pair of frame pieces 1 and 2 having upstanding flanges 3 and 4 respectively, which are adapted to receive arcuate binder posts 5 and to support cover members 6 and 7. Frame pieces 1 and 2 are also provided with downwardly extending flanges, 8 and 9 respectively, terminating in hinge knuckles 10 and 11 by means of which 80 they are joined in pivotal relationship to form a hinge 12.

Covers 6 and 7 are secured to strips 15 and 16 respectively by any suitable means, said strips being pivotally secured to upstanding flanges 3 and 4 by means of cooperating hinge knuckles 17 and 18 and pintle wires 19 and 20.

85 Arcuate posts 5 are provided with an integrally formed shoulder 25 and plane-surfaced shanks 26 which are adapted to be passed through apertures of corresponding cross section in flanges 3 and 4 and riveted into engagement therewith as shown in Fig. 7. The plane-surfaced shanks of posts 5 have 90

been shown as square in cross-section, although it is obvious that other non-circular forms may be employed for automatically aligning the posts in the desired position. The posts are preferably formed by upsetting the end portion to produce a shoulder and a shank which is shaped as desired. A series of suitable holes are provided in flanges 3 and 4 for receiving these posts and securing them in operative position in the binder. Flanges 3 and 4 are also provided with enlarged apertures 28 which provide clearance for the ends of the posts when the binder is in closed position.

15 The latching mechanism comprises a pair of bell-crank levers 30, 31 which are pivoted as by rivets 32, 33 to the underside of frame piece 2 at points preferably widely spaced longitudinally thereof. Said bell-crank levers 30, 31 are provided with arcuate arms 34 which are extended through suitable apertures in flange 9 of frame piece 2 and are provided with catches 36, 37, which engage the side of suitable slots 38 in flange 8 of frame piece 1. Springs 40 cooperate with said bell-crank levers and with frame piece 2 for normally maintaining said levers in engaging position. Link 41, pivotally connected to arms 34 of levers 30, 31, causes said levers to move as a unit.

35 Arm 42 of lever 30 is extended outwardly past frame piece 2 and is suitably bent at its end portion to provide thumb piece 43 by means of which the latching mechanism above described may be manually controlled. Thumb piece 43 moves in a horizontal direction transverse to the axis of hinge 12. Consequently, the latching mechanism may be released by transverse pressure on the thumb piece with the same movement that is required to open the binder.

40 Catches 37 are so positioned that they engage the sides of slots 38 to secure the binder in closed position. Catches 36 are provided at the end of arms 34 and secure the binder in partly open position as shown in Fig. 4. In this position pins 5 overlap slightly thereby preventing the filler sheets from being removed, while the pressure on these sheets is sufficiently relieved to allow them to lie in a substantially flat position on covers 6 and 7.

45 Back pieces 45 are secured to frame pieces 1 and 2 and provide a partial closure for the latching mechanism and a support for the back of the binder. These members may be secured to frame pieces 1 and 2 in any convenient manner as by rivets 46. End closures 47 are secured to frame pieces 1 and 2 in any convenient manner to form a complete closure 50 for the latching mechanism thereby protecting the same from injury and causing the exposed parts of the binder to present a neat appearance. Back pieces 45 are extended beyond frame pieces 1 and 2 flush with thumb piece 43 to provide finger-engaging sections

48. Sections 48, in addition to concealing thumb piece 43 and protecting the same against accidental displacement, provide a convenient surface for gripping the binder when the same is to be opened or closed.

70 The binder above described is normally held in closed position by catches 37 on bell-crank levers 30 and 31, which are held by springs 40 in engaging position with flange 8 of frame piece 1. When it is desired to make entries in the binder the sheets comprising the filler may be caused to lie flat along covers 6 and 7 by extending the binder to partly open position. This is accomplished by gripping finger pieces 48 and thumb piece 43 and exerting transverse pressure thereon which causes suitable rotation of bell-crank levers 30 and 31, and to release the catches 37 and produces pivotal movement of the frame pieces about hinge 12. The binder is thus extended to the position in which catches 36 are then engaged by flange 8 of frame piece 1, thereby securing the binder against further opening. Since the posts are in partly interleaved position the sheets may be turned as desired, but cannot be removed from the binder.

75 80 85 90 95 When it is desired to completely open the binder to the position shown in Fig. 2, finger pieces 48 and thumb piece 43 are again gripped and transverse pressure applied to release catches 36 and to cause further pivotal movement of the frame pieces about hinge 12. To close the binder it is only necessary to apply pressure in the proper direction to back pieces 45, since springs 40 cause the latching mechanism to be automatically operated. The binder is accordingly locked in either partly open or in closed position without further manipulation of thumb piece 43.

100 105 110 115 120 125 It is to be noted that the above described mechanism provides a simple and efficient means for operating a binder whereby a single motion of the hands may be employed for releasing the catch and forcing the binder into open position. This is effected by reason of the catch being so positioned that horizontal movement transverse to the axis of the hinge is employed for releasing the same. This eliminates the tendency of the binder to slip over the surface on which it is resting when the necessary pressure is employed for releasing the catches since the force applied to the catch is utilized entirely in forcing the binder into open position.

By forming the posts as above described of single elements on which the shoulders and square ends are integrally formed the necessity for using a plurality of separate elements, such as washers, is avoided and the construction simplified. The square shanks cause the posts to be automatically aligned in the required position without the use of 130

any measuring or aligning and further simplifies the assembling operation.

Although a particular type of catch has been shown for purposes of illustration, it is obvious that the invention may be applied to other types of catches, and that various forms of posts may be employed in accordance with the purpose for which the binder is to be employed.

10 While certain novel features of the invention have been shown and described and are pointed out in the annexed claims, it will be understood that various omissions, substitutions and changes in the forms and details of 15 the device illustrated and in its operation may be made by those skilled in the art without departing from the spirit of the invention.

What is claimed is:

1. In a loose leaf binder, a pair of frame 20 pieces, hinged means for interconnecting said frame pieces, and latching mechanism carried by one of said frame pieces and cooperating with the other of said frame pieces comprising a pair of levers spaced longitudinally of said frame pieces and having arcuate arms extending beyond one of said frame pieces into engagement with the other of said frame pieces.

2. In a loose leaf binder, a pair of frame 30 pieces, hinge means for interconnecting said frame pieces, and latching mechanism carried by one of said frame pieces and cooperating with the other of said frame pieces, comprising a pair of levers spaced longitudinally of said frame pieces and having arcuate arms extending beyond one of said frame pieces into engagement with the other of said frame pieces, one of said levers having a second arm extending at approximately 40 right-angles to said first arm and provided at its end with a thumb piece which is movable about the pivot of said lever in a direction transverse to the axis of the binder hinge.

3. In a loose leaf binder, a pair of frame 45 pieces, hinge means for pivotally interconnecting said frame pieces, a pair of levers having arcuate arms pivotally secured to one of said frame pieces and provided with catches engaging the other of said frame 50 pieces, a control arm carried by one of said levers and extending at right-angles to said arcuate arms and a link interconnecting said levers for causing unitary operation thereof.

4. In a loose leaf binder, a pair of frame 55 pieces having downwardly extending flanges and upwardly extending flanges, hinged means interconnecting said downwardly extending flanges, covers secured to said upwardly extending flanges, latching mechanism pivotally carried by one of said frame pieces and extending through its downwardly extending flange into engagement with the other of said frame pieces, said mechanism comprising an arcuate arm having a plurality 60 of catch members thereon and a con-

trol arm extending at right angles thereto and provided with a thumb piece accessible from the end of said binder.

5. In a loose leaf binder, a pair of frame 70 pieces having downwardly extending flanges and upwardly extending flanges, covers secured to said upwardly extended flanges, latching mechanism pivotally carried by one of said frame pieces and extending through its downwardly extending flange into engagement with the other of said frame pieces, said mechanism comprising an arcuate arm having a plurality 75 of catch members thereon and a control arm extending at right angles thereto and provided with a thumb piece accessible from the end of said binder, said thumb piece being movable in a direction transverse to the binder hinge whereby the same movement may be employed by releasing said latching mechanism and for opening 80 said binder.

6. In a loose leaf binder, a pair of frame 85 pieces having downwardly extending flanges and upwardly extending flanges, hinged means interconnecting said downwardly extending flanges, covers secured to said upwardly extending flanges, latching mechanism pivotally carried by one of said frame pieces and extending through its downwardly 90 extending flange into engagement with the other of said frame pieces, said mechanism comprising an arcuate arm having a plurality of catch members thereon and a control arm extending at right angles thereto and provided with a thumb piece accessible from the end of said binder, and back pieces secured to said frame pieces and forming a partial closure for the latching mechanism and a support for the binder back.

7. In a loose leaf binder, a pair of frame 95 pieces having downwardly extending flanges and upwardly extending flanges, hinged means interconnecting said downwardly extending flanges, covers secured to said upwardly extending flanges, latching mechanism pivotally carried by one of said frame pieces and extending through its downwardly extending flange into engagement with the other of said frame pieces, said mechanism comprising an arcuate arm having a plurality 100 of catch members thereon and a control arm extending at right angles thereto and provided with a thumb piece accessible from the end of said binder, and back pieces secured to said frame pieces and forming a partial closure for the latching mechanism and a support for the binder back.

105 8. In combination with a device of the class described a pair of longitudinally hinged frame pieces, a plurality of leaf posts secured to said frame pieces, a plurality of spring compressed bell crank levers, links mutually connecting said bell crank levers for co-operative 110

115 120 125 130

action, arcuated latch members formed on an arm of said bell crank lever, said latch members having a first catch member which locks the frame pieces against relative displacement, and a second catch element adapted to maintain said frame pieces in an intermediate position against further outward displacement, an arm on one of said bell crank levers extending beyond the longitudinal end of 10 said frame pieces to present an exposed portion whereby said catches may be released by transverse pressure on said exposed portion.

9. In combination with a device of the 15 class described, a pair of longitudinally hinged frame pieces, a plurality of leaf posts secured to said frame pieces, a plurality of spring pressed bell crank levers, links mutually connecting said bell crank levers for 20 co-operative action, latch members integral with said bell crank lever, said latch members having a first catch member which locks the elements of the binder against relative displacement, and a second catch element 25 adapted to maintain the frame pieces in an intermediate position against further outward displacement, means for releasing said first and second catch elements, said means being rendered operative by transverse pressure 30 on one of said crank levers, and means for automatically rendering operative said catch elements successively when the frame pieces are swung into closed position.

In testimony whereof I have hereunto set 35 my hand.

CHARLES EDWIN SHEPPARD.
